(57) **ABSTRACT**

Embodiments are provided for a one-piece clothing garment that forms an integrated headband and scarf. Additionally, the headband and scarf are formed in a way that the headband is sewn at an upward angle forming an indent at the connection point that provides neck protection without air leakage. Also, a method of forming a one-piece clothing garment that has a scarf portion and a headband portion is disclosed.

ONE-PIECE LOOPED SCARF**CROSS-REFERENCE TO RELATED APPLICATIONS**

This application is a continuation in part patent application which claims priority to U.S. Non-Provisional Pat. No. 11,026,456 issued on Jun. 8, 2021, and is incorporated by reference in its entirety. This patent was previously filed as U.S. Non-Provisional patent application Ser. No. 16/170,551 on Oct. 25, 2018.

FIELD OF THE DISCLOSURE

This disclosure relates generally to the field of clothing and garments. More specifically, the present disclosure relates to a one-piece garment that has the features of a scarf and a headband, and a method of making said garment.

BACKGROUND

People who live in cold climates know the value of keeping your neck and forehead warm. Various types of garments (e.g. scarves, headbands, hats) have been developed that cover the neck and the wearer's head to keep them warm. These garments are very important in staying warm in a cold climates or cold buildings, and especially important for young children who are more susceptible to the cold. If, for example, a child's neck and head are exposed to cold weather, they are at risk of catching a cold or other illness as their immune system can be lowered from exposure to low temperatures.

Thus, wearers of hats and scarves, and other winter garments, value how important it is to keep their necks and head warm in cold weather. Traditional combinations of garments is effective, however, drawbacks persist with their use. Scarves may come unraveled with activity and often prove difficult to readjust for proper facial coverage. Hats often leave the user's hair in a flattened and unkept condition. Additionally, the combination of using a hat and a scarf, as two separate garments, can leave a separation between the two garments that allows for cold air to pass through.

There have been some attempts to provide alternatives. For example, U.S. Pat. No. 7,096,511 discloses a clothing garment that is formed in two loops or bands as a unitary garment. Specifically, this patent discloses a clothing garment comprising a unitary garment formed of two fabric units that are combined to form an integrated garment. This patent uses two loops of fabric which are removably fastened at one section of the loops and is adjustable via the fastener.

Although this patent application includes a scarf in the form of a two-looped garment, whereby said first loop and said non-rectangular second loop are attached together via a fastener, this patent application still includes several disadvantages as that of a traditional scarf and hat combination. More specifically, by being formed of two separate fabric units, one unit being non-rectangular, and having the garment fabric units be detachable from one another, this patent fails to provide a one-piece solution that does not allow air to leak through the neck region of the garment.

Due to all of the existing shortcomings in presently available garments, there is still a need for a clothing garment that provides a solution for the problems present in the prior art.

SUMMARY

The disclosure presented herein relates to a clothing garment that comprises of a headband portion and a scarf

portion, allowing a user to wear the clothing garment in a plurality of positions. One such position includes wearing the clothing garment as a headband and a scarf combination whereby the clothing garment covers the neck and the head of a wearer. Wearing the clothing garment in such a combination is especially beneficial in a cold environment, wherein a wearer's neck, ears, and forehead are sheltered from the cold air and kept warm. Those of ordinary skill will appreciate that clothing garment can be worn in other positions, in varied weather conditions, and for fashionable wear. Thus, other uses may be foreseeable and are included within the scope of the present description.

In one aspect, the present invention relates to a method of making a clothing garment comprising of a headband portion and a scarf portion.

In one aspect, one or more embodiments for a one-piece garment are provided in the present description, whereby the one-piece garment includes a forehead portion and a scarf portion. The forehead portion having a first loop that is comprised of a first elongated side and a second elongated side, whereby said first elongated side and second elongated side are sewn together to form a tube. Further, the one-piece garment includes a scarf portion that includes a first elongated side and a second elongated side, whereby the first elongated side and second elongated side are sewn together to form a second a first tube. Further, the scarf portion and the head band portion are formed from one-piece of fabric.

The preceding and following embodiments and descriptions are for illustrative purposes only and are not intended to limit the scope of this disclosure. Other aspects and advantages of this disclosure will become apparent from the following detailed description.

BRIEF DESCRIPTION OF THE DRAWINGS

Embodiments of the present disclosure are described in detail below with reference to the following drawings. These and other features, aspects, and advantages of the present disclosure will become better understood with regard to the following description, appended claims, and accompanying drawings. The drawings described herein are for illustrative purposes only of selected embodiments and not all possible implementations and are not intended to limit the scope of the present disclosure.

FIG. 1 is a side view of a one-piece clothing garment according to various aspects of the present invention.

FIG. 2 is a top view of a piece of cloth used to make a one-piece clothing garment according to various aspects of the present invention.

FIG. 3 is a front view of a one-piece clothing garment as it would appear on a wearer, according to various aspects of the present invention.

FIG. 4 is a side view of an alternative embodiment of a one-piece clothing garment according to various aspects of the present invention.

FIG. 5 is a front view of an alternative embodiment of a one-piece clothing garment with pockets.

FIG. 6 is a side view of the alternative embodiment of a one-piece clothing garment with pockets.

DETAILED DESCRIPTION

In the Summary above and in this Detailed Description, and the claims below, and in the accompanying drawings, reference is made to particular features (including method steps) of the invention. It is to be understood that the disclosure of the invention in this specification includes all

possible combinations of such particular features. For example, where a particular feature is disclosed in the context of a particular aspect or embodiment of the invention, or a particular claim, that feature can also be used, to the extent possible, in combination with and/or in the context of other particular aspects and embodiments of the invention, and in the invention generally.

The term "comprises" and grammatical equivalents thereof are used herein to mean that other components, ingredients, steps, among others, are optionally present. For example, an article "comprising" (or "which comprises") components A, B and C can consist of (i.e., contain only) components A, B and C, or can contain not only components A, B, and C but also contain one or more other components.

Where reference is made herein to a method comprising two or more defined steps, the defined steps can be carried out in any order or simultaneously (except where the context excludes that possibility), and the method can include one or more other steps which are carried out before any of the defined steps, between two of the defined steps, or after all the defined steps (except where the context excludes that possibility).

The term "at least" followed by a number is used herein to denote the start of a range beginning with that number (which may be a range having an upper limit or no upper limit, depending on the variable being defined). For example, "at least 1" means 1 or more than 1. The term "at most" followed by a number (which may be a range having 1 or 0 as its lower limit, or a range having no lower limit, depending upon the variable being defined). For example, "at most 4" means 4 or less than 4, and "at most 40%" means 40% or less than 40%. When, in this specification, a range is given as "(a first number) to (a second number)" or "(a first number)-(a second number)," this means a range whose limit is the second number. For example, 25 to 100 mm means a range whose lower limit is 25 mm and upper limit is 100 mm.

Certain terminology and derivations thereof may be used in the following description for convenience in reference only and will not be limiting. For example, words such as "upward," "downward," "left," and "right" would refer to directions in the drawings to which reference is made unless otherwise stated. Similarly, words such as "inward" and "outward" would refer to directions toward and away from, respectively, the geometric center of a device or area and designated parts thereof. References in the singular tense include the plural, and vice versa, unless otherwise noted.

The present description includes one or more embodiments for a one-piece clothing garment that may be worn by a user, where the headband portion can be easily pulled down to allow a user to cover their ears or other aspects of their head, while the scarf portion stays in place and covers the wearer's neck. The one or more embodiments for a one-piece clothing garment include multiple elements. For example, in one or more embodiments, various headband shapes or materials may be formed to better protect a wearer's head. Elements included herein are meant to be illustrative, rather than restrictive. Persons having ordinary skill in the art relevant to the present disclosure may understand there to be equivalent elements that may be substituted with the present disclosure.

As best seen in FIG. 1, a one-piece clothing garment 10 can be seen having a headband portion 1 and a scarf portion 3. The headband portion 1 and scarf portion 3 are integrated at connection point 6, with the headband portion inside of the scarf portion. The headband portion 1 is made out of a first loop 4, and the scarf portion 3 is made out of a second

loop 2. In this embodiment, the first loop 4 is connected with the second loop 2 at connection point 6. This connection point 6 runs the entire width of the first loop 4, as the one-piece garment is formed from one-piece of clothing material.

The one-piece clothing garment also contains an indent 7. This indent 7 is the result of the one-piece clothing garment 10 being formed from one-piece of clothing material (as described below) and is formed when non-integrated end 10 (FIG. 2 number 24) of the first loop 4, and the non-integrated end (FIG. 2 number 29) of the second loop 2 are connected at the integrated ends 31 and 21, respectively, of FIG. 2. The indent 7 formed during the formation of the one-piece clothing garment 10 serves the purpose of keeping a wearer's neck covered due to the first and second loops being formed from one-piece of clothing material. This one-piece design prevents the passage of air to the user's neck as there is no open space for air to leak through.

In one non-limiting embodiment, the scarf portion and the headband portion both have widths that are constant without any portions that are substantially wider.

The two loops can be in an overlying relationship and the first loop 4 can be used to cover the ears of the wearer. The second loop 2, can be used to protect the neck of the wearer.

In one embodiment, the headband portion 1, and the scarf portion 3, are formed out of one-piece of clothing material. This clothing material can include any known fabrics commonly used to make a scarf or headband. This embodiment can include stretchable fabrics or non-stretchable fabrics. 30 This is advantageous as using one-piece of clothing material to form the one-piece clothing unit 10 allows for a seamless integrated connection of the headband portion 1, and the scarf portion 2, as one-piece of clothing material is used for the entire garment without being separated. This will prevent 35 air leakage at the back of the neck of the wearer.

In a further embodiment non-limiting embodiment, the headband portion and the scarf portion are formed out of two different materials.

Turning to FIG. 2, FIG. 2 shows a top view of a piece of 40 clothing material 20 used to make a one-piece clothing garment. In this embodiment, a one-piece clothing garment, as shown in FIG. 1 is formed out of the one-piece clothing material 20, and comprises a first slit 15 and a second slit 16, a headband portion 18 comprising; a first loop (FIG. 1 number 4) formed by an elongated first side 26 and second side 22 that are sewn together to form a first tube shape having an integrated end 31 and a first non-integrated end 24; a scarf portion 19 made of a second loop (FIG. 1 number 2), said second loop being made of an elongated third side 50 27 and fourth side 28 that are sewn together to form a second tube shape having a second non-integrated end 21 and third non-integrated end 29. In this embodiment, the connection point 30 is sewn together with first integrated end 31 to form said first loop and said third non-integrated end 29 is sewn 55 together with said connection point 30 and said second non-integrated end 21 to form said second loop.

In forming the one-piece clothing garment shown in FIG. 1, a single piece of clothing material as shown in FIG. 2 must first be cut out. The one-piece of clothing material can be 60 any fabric acceptable in common use of a headband or scarf. In one embodiment, the single piece of fabric includes any combination of polyesters, cottons, wool, denim, leather, down, fur, nylon, spandex, or any other material acceptable to form a one-piece of clothing material. In the FIG. 2 embodiment, the clothing material is cut into a scarf portion 19, and a headband portion 18. In some embodiments, the scarf portion 19 and headband portion 18 may be of equal

width. In some embodiments, the scarf portion **19** or the headband portion **18** may be wider than the other, for example to have extra material for comfort and styling. In some embodiments, the shape of the clothing material may be cut to accommodate a greater or narrower width to cover the ears or any other reason. In this embodiment, before the one-piece of clothing material is formed into the one-piece clothing garment, the headband portion **18** has a first elongated side **26** and second elongated side **22**, and a first non-integrated end **24** and an integrated end **31**. The integrated end is designated integrated as this end is integrated with the scarf portion **19** at connection point **30**. Further, in this embodiment, the scarf portion has a third elongated side **27** and forth elongated side **28**, as well as a second non-integrated end **21** and a third non-integrated end **29**.

After the shape of the one-piece clothing material **20** is cut out of a clothing material, a first slit **15** and a second slit **16** are cut at connection point **30** between the scarf portion and the headband portion. In one non-limiting embodiment, these slits on both sides are around 2 inches. These slits are cut in order to allow the formation of the first and second loop as detailed below, and in one non-limiting embodiment, are only cut partially through the width of the fabric and do not sever the clothing material into two pieces. In other non-limiting embodiments, the one-piece clothing material **20** may not have slits cut at the connection point **30** between the scarf portion and the headband.

After the slits **15** and **16** are cut, the headband portion **18** is formed into a tube shape by sewing together the first **26** and second **22** elongated sides to form said tube shape having connection point **30** and first non-integrated end **24**. In another embodiment, the elongated sides are not sewn, but are connected together in any known method commonly used to make clothing garments.

The scarf portion **19** is then formed into a tube shape by sewing together the third elongated side **27** with the forth elongated side **28** to form said tube shape having second non-integrated side **21** and third non-integrated side **29**.

In one embodiment, after the tube shape of the headband portion **18** and the loop shape of the scarf portion **19** are formed by sewing together the elongated sides detailed above, both of the tube shapes are pulled inside out in order to hide the sewing seams.

After the completion of the above steps, in one embodiment, the first loop is formed by attaching the end of the first non-integrated end **24** to the top of the connection point **30**.

In one non-limiting embodiment, the single stitching instead of double stitching is used to form the one-piece clothing garment shown in FIG. 1. In a further embodiment, any other attachment means commonly used in the formation of clothing garments can be used.

In one embodiment, the second loop is formed by attaching the third non-integrated end **29** to the connection point **30** and the second non-integrated end **21**. In a further embodiment, the lower portion of the third non-integrated end **29** is double stitched to the lower portion of the second non-integrated end **21**, forming a scarf, and the upper portion of the third non-integrated end **29** is double stitched with the connection point **30** and the first non-integrated end **24**, forming a headband.

FIG. 3 is a front view of a one-piece clothing garment **30** as it would appear on a wearer, according to various aspects of the present invention. In this view, the scarf portion **32** can be seen around the wearer's neck, and the headband portion **34** can be seen as it would appear on the wearer's head. In this embodiment, the scarf portion **32** would keep the wearer's neck warm, and the headband portion **34** would

keep the wearer's forehead warm. Additionally, in this embodiment, the clothing garment is made out of one-piece of fabric, so wearers neck would be kept warm where the scarf portion **32** transitions into the headband portion **34**.

5 In one non-limiting embodiment, the clothing garment **30** may be configured such that the scarf portion **32** when worn substantially covers the neck area of a wearer. In a second non-limiting embodiment, the clothing garment **30** may be configured such that the scarf portion is worn loose. A length 10 of the third elongated side **27** and a length of the fourth elongated **28**, as shown in FIG. 2, may be adjusted in parallel to provide a tighter fit or a looser fit to the scarf portion **32**.

In a further non-limiting embodiment shown in FIG. 4, a means to facilitate putting on the one-piece clothing garment 15 is configured at a location on the one-piece clothing garment. As shown in FIG. 3, the clothing garment of the present disclosure is generally worn by slipping the scarf portion **32** and the headband portion **34** over a wearer's head to where the scarf portion **32** may be pulled down to and 20 worn around a neck area of the wearer. Referencing FIG. 4, a clothing garment **40** is shown with a scarf portion **42** and a headband portion **44**. In order to facilitate the slipping of the clothing garment **40** over a head area of the wearer, a section of the scarf portion **42** comprises an openable 25 enclosure **46** such as, but not limited to, a zipper, one or more snaps, VELCRO, one or more hooks, one or more buttons, and any other means known in the art for closing a garment or piece of clothing.

In this non-limiting embodiment, the clothing garment **40** 30 shown in FIG. 4 is made similarly as described in FIG. 2. The headband portion **44** is made out of a first loop that comprises a headband tube formed by sewing an elongated top side (such as, elongated first side **26** in FIG. 2), and an elongated bottom side (such as, elongated second side **22** in 35 FIG. 2) together to form the headband tube having two ends (such as integrated end **31** and first non-integrated end **24** in FIG. 2) that are connected together by sewing the two ends by double or single stitching. The scarf portion **42** is also 40 similarly made as described in FIG. 2, however the openable enclosure **46** is configured onto the scarf portion **42**. The scarf portion **42** is made out of a second loop that comprises a scarf tube formed by sewing an elongated top side (such as, elongated third side **27** shown in FIG. 2) and an elongated bottom side (such as, elongated fourth side **28** shown 45 in FIG. 2) to form the scarf tube having two ends (such as, second non-integrated end **21** and third non-integrated end **29** shown in FIG. 2) wherein the two ends are not connected 50 together by sewing the two ends. The two ends of the scarf tube are configured with the openable enclosure **46**. The openable enclosure **46** essentially provides an opening **48** in the scarf portion such as to facilitate the wearing of the clothing garment **40**. The headband portion **44** first loop is 55 connected with the scarf portion **42** second loop at a connection point (such as, connection point **31** shown in FIG. 2), wherein an end of the scarf tube opposite the connection point is connected to the headband portion **44**. However, the opening **48** in the scarf portion **42** will be closed by closing the openable enclosure **46**.

The openable enclosure **46** can be opened to facilitate a 60 wearer to slip the clothing garment **40** over a head area to wear the scarf portion around a neck area and then subsequently close the openable enclosure **46**. Additionally, the openable enclosure **46** can also be opened to facilitate removing the clothing garment **40** over a head area. The openable enclosure **46** is attached to the two ends of the scarf tube by any means known in the art such as and not limited to stitching and fabric glue. As seen in FIG. 4, a zipper is

provided as an example of the openable enclosure 46 wherein the zipper is connected to the two ends of the scarf tube which may include a third non-integrated end 29 and the second non-integrated end 21 as shown in FIG. 2.

Alternatively, a longer openable enclosure may be provided to create a longer opening in the clothing garment to facilitate the wearing of the clothing garment over a head area. In this alternative embodiment, the openable enclosure 46 is configured on the two ends of the scarf tube including the connection point (such that the headband portion first loop is connected to the connection point and the scarf portion second loop is connected to the headband portion via the openable enclosure 46).

In additional non-limiting embodiments, the clothing garment 40 is also provided with one or more pockets. In one aspect shown in FIGS. 5-6, at least two pockets, a first pocket 48 and a second pocket 49, may be configured in the scarf portion 42 of the clothing garment 40. A first pocket 48 may be configured in an area of the scarf portion 42 that corresponds to and aligns with a front side of a wearer's neck such that the scarf portion 42 with the first pocket 48 can be pulled over a mouth and a nose of a wearer. The first pocket 48 is configured on an inside facing portion of the scarf portion 42 and is dimensioned to allow a mask filter to be placed through the first pocket 48. The dimensions for the first pocket 48 may include in the range of 3.5 inches to 5 inches by 2.5 inches to 3 inches. An example of the dimensions for a first pocket 48 which can accommodate a mask filter may include a size of 4 inches by 2.75 inches.

The first pocket 48 may have an enclosure means to prevent the filter from slipping, including and not limited to a VELCRO device, one or more snap buttons, a foldable flap, other fastener devices, and any other means known in the art. The clothing garment 40 may be worn with the scarf portion 42 covering the neck, the mouth and the nose of a wearer. In this wearable position a wearer can achieve several benefits such as keeping the neck, mouth, and nose area warm and also importantly, preventing exposure to airborne contaminants such as the inhaling or exhaling of viral or other unwanted particles with the mask filter placed in the first insert 48.

Furthermore, the second pocket 49 may be configured in an area of the scarf portion 42 that when worn is positioned on a side of the neck area of a wearer. Alternatively, the second pocket 49 may also be configured in an area of the scarf portion 42 that is nearer the openable enclosure (such as openable enclosure 46 shown in FIG. 4). Preferably, the second pocket 49 may be configured on the inside facing portion of the scarf portion 42. Alternatively, the second pocket 49 may be configured on an outside facing portion of the scarf portion 42. The second pocket 49 is dimensioned to receive, accommodate, or accept items such as a driver license, a credit card, money, an automotive key, a regular key, and any other small item. The dimensions for the second pocket 49 may include in the range of 3.45 inches to 4 inches by 2 inches to 2.5 inches. An example of the dimensions for a second pocket 49 may include a size of 3.45 inches by 2.25 inches.

The second pocket 49 may have an enclosure means to secure items received within. The enclosure means may include and not be limited to a VELCRO device, one or more snap buttons, a foldable flap, other fastener devices, and any other means known in the art.

In another aspect, the clothing garment described in the various non-limiting embodiments may also be comprised of a liner (not shown in the figures). The liner is designed to line the inside facing portion of the clothing garment. The

liner may be connected to the inside facing portion of the clothing garment by any means known in the arts, including and not limited to sewing and fabric glue. The liner may line the inside facing portion of the scarf portion, the headband portion, or both. The liner may preferably be a Dri-Fit material, however other materials are also contemplated and may be used as a liner.

Advantageously, the present description provides one or more embodiments of various types of one-piece clothing garments. Each clothing garment depicted herein provides advantages that overcome shortcomings of other types of clothing garments that are used conventionally. Further, the various embodiments shown in the figures and described herein accommodate different sized heads or necks and may be used in various applications, including, but not limited to keeping a wearer's head and neck warm. It is noted that the various embodiments of clothing garments presented herein may be used in many other ways other than to keep a wearer's head warm. Thus, the various embodiments described in the present description include a number of novel and helpful components that provide enhanced pants garment to benefit a user.

The corresponding structures, materials, acts, and equivalents of all means or step plus function elements in the claims below are intended to include any structure, material, or act for performing the function in combination with other claimed elements as specifically claimed. The description of the present invention has been presented for purposes of illustration and description but is not intended to be exhaustive or limited to the invention in the form disclosed. Many modifications and variations will be apparent to those of ordinary skill in the art without departing from the scope and spirit of the invention. The embodiments were chosen and described in order to best explain the principles of the invention and the practical application, and to enable others of ordinary skill in the art to understand the invention for various embodiments with various modifications as are suited to the particular use contemplated. The present invention according to one or more embodiments described in the present description may be practiced with modification and alteration within the spirit and scope of the appended claims. Thus, the description is to be regarded as illustrative instead of restrictive of the present invention.

What is claimed is:

1. A clothing garment, comprising:
a headband portion and a scarf portion, wherein the headband portion is formed of a first loop that comprises a headband tube formed by sewing an elongated top side and an elongated bottom side together to form the headband tube having two ends that are connected together, wherein the scarf portion is formed of a second loop that comprises a scarf tube formed by sewing an elongated top side and an elongated bottom side to form the scarf tube having two ends wherein the two ends are configured with an openable enclosure such that the openable enclosure connects the two ends together; and wherein the headband portion first loop is connected with a portion of the scarf portion second loop at a connection point.
2. The clothing garment of claim 1, wherein the openable enclosure comprises an opening in the clothing garment to provide ease of slipping the scarf portion over a wearer's head.
3. The clothing garment of claim 1, wherein the openable enclosure having a zipper, a hook and loop fastener, one or

more snap buttons, one or more hooks, or one or more button and buttonholes to open or close the opening.

4. The clothing garment of claim 1, wherein the two ends of the headband tube are sewn together to form the headband loop portion, wherein the two ends of the scarf tube are provided with the openable enclosure to form the scarf loop portion when the openable enclosure is closed, and wherein the headband loop portion and the scarf loop portion including a portion of the openable enclosure are sewn together to form the connection point between the headband loop portion and the scarf loop portion.

5. The clothing garment of claim 1, wherein a liner lines an inside facing portion of the scarf portion and the headband portion.

6. A method of making a clothing garment, comprising: cutting out a clothing material comprising a scarf portion and a headband portion from a piece of fabric; sewing together an elongated top side and an elongated bottom side of the headband portion to form a headband tube having two ends; sewing together an elongated top side and an elongated bottom side of the scarf portion to form a scarf tube having two ends; forming a headband loop by sewing together the two ends of the headband tube; forming a scarf loop by connecting an openable enclosure at the two ends of the scarf tube; and connecting the headband loop and the scarf loop including a portion of the openable enclosure at a connection point.

7. The method of claim 6, wherein the sewing together of the two ends of the headband loop and the sewing together of the two ends of the scarf loop with a portion of the openable enclosure occurs at the connection point.

8. A clothing garment comprising: a headband portion and a scarf portion, wherein the headband portion is formed of a first loop that comprises a headband tube formed by sewing an elongated top side and an elongated bottom side together to form the headband tube having two ends that are connected together; wherein the scarf portion is formed of a second loop that comprises a scarf tube formed by sewing an elongated top side and an elongated bottom side to form the scarf tube having two ends that are connected together; wherein the headband portion first loop is connected with the scarf portion second loop at a connection point; and wherein the scarf portion is configured with one or more pockets formed on an inside facing portion of the scarf portion.

9. The clothing garment of claim 8, wherein a first pocket of the one or more pockets is configured on the inside facing portion of the scarf portion and is configured to correspond to and aligns with a mouth and nose of a wearer when the scarf portion is pulled upward from a neck of said wearer.

10. The clothing garment of claim 9, wherein the size and shape of the first pocket is configured to fit a mask filter to block airborne contaminants.

11. The clothing garment of claim 8, wherein a second pocket of the one or more pockets is configured on the inside facing portion of the scarf portion and is configured to correspond to and aligns with a side of a neck area of said wearer.

12. The clothing garment of claim 11, wherein the size and shape of the second pocket is configured to fit small items comprising driver license, keys, and cash.

13. The clothing garment of claim 8, wherein the one or more pockets are secured by a foldable flap, a hook and loop fastener, one or more snaps, or a zipper.

14. A clothing garment, comprising: a headband portion and a scarf portion, wherein the headband portion is formed of a first loop that comprises a headband tube formed by sewing an elongated top side and an elongated bottom side together to form the headband tube having two ends that are connected together;

wherein the scarf portion is formed of a second loop that comprises a scarf tube formed by sewing an elongated top side and an elongated bottom side to form the scarf tube having two ends wherein the two ends are secured by an openable enclosure;

wherein the headband portion first loop is connected with a first end of the scarf portion second loop including a portion of the openable enclosure at a connection point; and

wherein the scarf portion is configured with one or more pockets formed on an inside facing portion of the scarf portion.

15. The clothing garment of claim 14, wherein a first pocket of the one or more pockets is configured on the inside facing portion of the scarf portion and is configured to correspond and aligns with a mouth and nose of a wearer when the scarf portion is pulled upward from a neck of said wearer.

16. The clothing garment of claim 15, wherein the size and shape of the first pocket is configured to fit a mask filter to block airborne contaminants.

17. The clothing garment of claim 14, wherein a second pocket of the one or more pockets is configured on the inside facing portion of the scarf portion and is configured to correspond to and aligns with a side of a neck area of a wearer.

18. The clothing garment of claim 17, wherein the size and shape of the second pocket is configured to fit small items comprising driver license, keys, and cash.

19. The clothing garment of claim 14, wherein the one or more pockets are secured by a foldable flap, a hook and loop fastener, one or more snaps, or a zipper.
